UNITED STATES PATENT OFFICE.

GOTTFRIED FEDER, OF MUNICH, GERMANY.

APPARATUS FOR MAKING CONCRETE PILES IN THE GROUND.

1,140,303.

Specification of Letters Patent. Patented May 18, 1915.

Application filed April 10, 1913. Serial No. 760,292.

To all whom it may concern:

Be it known that I, GOTTFRIED FEDER, a subject of the German Empire, residing at 7 Theatinerstrasse, Munich, Germany, have 5 invented certain new and useful Improvements in Apparatus for Making Concrete Piles in the Ground, of which the following is a specification.

My invention relates to apparatus for 10 making concrete piles in the ground, and a primary object is to provide improved apparatus substantially consisting of a ramming core by means of which a sheet-metal casing or sleeve closed below is driven or 15 drawn into the ground.

The ramming core comprises three or 20 more T-girders whose flanges are so bent that they constitute a cylinder when the girders are placed with their ribs directed 25 radially relatively to one another. This ramming core is held together and protected from vibration by shackles, chains or the like placed around it and by a suitable spreading or splaying device.

25 The splaying device may consist of two truncated conical wedges which enter into corresponding recesses in the webs and are provided with longitudinal holes. A spindle is placed through these holes; the thread 30 on this spindle engages in the one of the wedges, while the other wedge bears against a collar fast on the spindle. The spindle also has a squared portion by means of which it is rotated, the two wedges moved 35 away from one another and the girders pressed apart against the shackles or the like.

35 The sheet-metal casing which is driven by the ramming core into the ground and remains therein is preferably provided on the outside with barbs which penetrate into the ground when the ramming core is being withdrawn and thereby prevent the casing being raised with the core.

45 One illustrative embodiment of my invention is represented by way of example in the accompanying drawing, wherein:—

Figure 1 is a vertical section showing the sheet-metal casing and the ramming core 50 therein; Fig. 2 is a horizontal section through the casing.

For driving the sheet-metal casing *i* into the ground a peculiarly formed ramming core is employed comprising three or more 55 T-girders *a*, four of them being shown in the embodiment. The flanges *c* of these

girders are bent in such manner that when the girders are placed with their webs radially, the flanges form a cylinder, as clearly shown in Fig. 2. The webs *b* of the girders 60 are provided with tapering, oppositely directed recesses *d*, *d'* in which fit truncated conical wedges *g*, *g'* provided with central longitudinal holes. In the illustrative embodiment the lower wedge *g'* is provided 65 with a threaded hole in which engages one end of a threaded spindle *f* whose other end passes through the other wedge *g* and bears with a collar *y* against this wedge *g*. The upper end of the spindle *f* has a squared 70 portion *z* by means of which the spindle can be turned. According to the direction of rotation of the spindle the wedges *g*, *g'* are either driven apart or toward one another. When the wedges *g*, *g'* move apart 75 they press against the webs *b* of the girders *a* and press the latter outward and consequently the flanges *c* toward the shackles *h*, *h* and against the inner periphery of the casing *i*. A thoroughly rigid structure is 80 thereby obtained and the ramming core prevented from being elastic. The casing *i* which remains in the ground runs out into a closed point *k* welded thereto and may be 85 provided with barbs *m* which owing to their entering into the ground prevent the casing being carried upward with the core when the latter is removed.

As shown in Fig. 1, the upper ends of the webs *b* and flanges *c* of the T-girders 90 are cut away so that a strong iron ring *n* can be placed thereon which simultaneously holds together the upper ends of the girders after a thick and heavy oak slab *o* for receiving the blows of the ram has been placed 95 upon said ring snugly fitting with its upper stepped portion against said ring.

For removing the spindle *f* and the wedges *g* and the ramming core, rings *x* mounted in the upper end of the spindle 100 are used.

A steel point *u* which fits into the point *k* of the casing *i* is mounted at the bottom end of the ramming core by means of eyes *v* and pins *w*. 105

After the shackles *h*, *h* have been placed about the casing *i* at suitable distances apart it is driven by means of the ramming core to the desired depth into the ground. The shackles *h*, which may be substituted by 110 chains or other suitable devices, are then removed in turn as the casing enters into the

ground. After the casing has reached the desired depth and the splaying device has been slackened the ramming core is removed by means of the rings α .

5 I claim:—

1. Apparatus for making concrete piles in the ground comprising a casing pointed at its lower end, a ramming core within said casing consisting of a number of girders 10 having flanges constituting a circle and radially disposed webs having recesses, wedges arranged in said recesses, shackles surrounding said casing at predetermined intervals, a means for adjusting said wedges 15 for spreading the girders against the action of said shackles to constitute a hollow shell, means for holding the upper ends of said girders together and means for receiving the blows of the ram.
2. Apparatus for making concrete piles in the ground comprising a casing pointed at its lower end, a ramming core within said casing consisting of a plurality of T-shaped girders forming a cylinder, a spindle guided 25 within said cylinder for spreading said girders apart, removable shackles constituting with said girders a hollow shell under spreading action, means for holding the upper ends of the girders together, a cover for 30 the upper end of said casing adapted to receive the blows of a ram, means secured to said spindle for permitting the withdrawal of the core from said casing and means for preventing said casing from following the 35 upward movement of said core during its withdrawal.
3. Apparatus for making concrete piles in the ground, comprising a casing pointed at its lower end, a ramming core within said 40 casing consisting of a plurality of T-shaped girders provided with flanges adapted to form with their outer faces curved on a circular arc, a cylinder, webs radially disposed and secured to said flanges, a spindle within 45 said cylinder for spreading said girders apart, removable means constituting with said girders a hollow shell under said spreading action, a ring surrounding the upper ends of said girders for holding the same 50 together, a cover for the top of said casing adapted to receive the blows of a ram and to snugly fit with its upper stepped part against said ring holding the same in position, means secured to said spindle for permitting the withdrawal of said core from 55 said casing, and barbs for preventing said casing from following the upward movement of said core during its withdrawal from the casing.
4. Apparatus for making concrete piles in the ground, comprising a casing pointed at its lower end, a ramming core within said casing consisting of a plurality of T-girders provided with flanges adapted to form with 60 their outer faces curved on a circular arc, a

cylinder, webs radially disposed and secured to said flanges, a spindle within said cylinder for spreading said girders apart, removable shackles surrounding said casing at predetermined intervals, constituting with said 70 girders a hollow shell under said spreading action, a ring surrounding the upper ends of said girders for holding the same together, a cover for the top part of said casing adapted to receive the blows of a ram and to snugly 75 fit with its upper stepped part against said ring holding the same in position, rings secured to said spindle for permitting the withdrawal of said core from said casing, and barbs for preventing said casing from 80 following the upward movement of said core during said withdrawal.

5. Apparatus for making concrete piles in the ground, comprising a casing pointed at its lower end, a ramming core within said 85 casing consisting of a plurality of T-shaped girders provided with flanges adapted to form with their outer faces curved on a circular arc, a cylinder, webs radially disposed and secured to said flanges having tapering, oppositely directed recesses, truncated conical wedges with central longitudinal holes and fitting in said recesses, a spindle secured to one of said wedges and extending through the other, a square head upon said spindle near its upper end presenting a means to rotate said spindle for approximating the two wedges, and a collar on said spindle supporting the conical wedge through which said spindle is extended, and means for withdrawing said spindle and core from said casing. 95

6. Apparatus for making concrete piles in the ground, comprising a casing, a point secured to said casing, a ramming core within said casing consisting of a plurality of T-shaped girders provided with flanges adapted to form with their outer faces curved on a circular arc, a cylinder, webs radially disposed and secured to said flanges 105 said flanges and webs being recessed at their upper ends, a ring surrounding the upper ends of the girders for holding their upper ends together, a cover for the top part of said casing adapted to receive the blows of a ram, and to snugly fit with its upper stepped part against said ring holding the same in position, seats on said webs, truncated, conical wedges provided with longitudinal slots in said seats, a spindle screwed 110 to one of said wedges and extending through the other, a square head upon said spindle near its upper end providing means for rotating said spindle, and a collar on said spindle supporting the conical wedge 115 through which said spindle is extended, rings providing means for withdrawing said spindle and said core from said casing, barbs upon the outer face of said casing for preventing the same from participating in 120 130

the upward movement of said core during my hand in presence of two subscribing witnesses.
the withdrawal thereof from said casing,
and removable shackles surrounding said
casing at predetermined intervals for con-
5 stituting with said girders a hollow shell
under said spreading action.

In testimony whereof I have hereunto set

GOTTFRIED FEDER.
